(57) **CLAIM**

The ornamental design for a planar magnetic transducer, as shown and described.

DESCRIPTION

FIG. 1 is a front perspective elevational view of a planar magnetic transducer showing our new design;

FIG. 2 is a front elevational view;

FIG. 3 is a rear elevational view;

FIG. 4 is a view taken from the right side;

FIG. 5 is a view taken from the left side;

FIG. 6 is a top plan view; and,

FIG. 7 is a bottom plan view.
